(57) **CLAIM**

The ornamental design for an air freshener in the shape of a racecar driver's jacket, as shown and described.

DESCRIPTION

FIG. 1 is a perspective view of an air freshener in the shape of a racecar driver's jacket;

FIG. 2 is a front elevational view of the air freshener in the shape of a racecar driver's jacket;

FIG. 3 is a rear elevational view of the air freshener in the shape of a racecar driver's jacket;

FIG. 4 is a top view of the air freshener in the shape of a racecar driver's jacket;

FIG. 5 is a bottom view of the air freshener in the shape of a racecar driver's jacket;

FIG. 6 is a left side view of the air freshener in the shape of a racecar driver's jacket; and,

FIG. 7 is a right side view of the air freshener in the shape of a racecar driver's jacket.

The elements illustrated in dashed lines in the accompanying drawings demonstrate environment and do not form part of the claimed design.
